UNITED STATES PATENT OFFICE.

CHARLES E. CHURCH, OF BOSTON, MASSACHUSETTS, ASSIGNOR TO THE HANCOCK INSPIRATOR COMPANY, OF SAME PLACE.

INJECTOR.

SPECIFICATION forming part of Letters Patent No. 405,990, dated June 25, 1889.

Application filed July 17, 1888. Serial No. 280,198. (Model.)

To all whom it may concern:

Be it known that I, CHARLES E. CHURCH, of Boston, in the county of Suffolk, and in the State of Massachusetts, have invented certain new and useful Improvements in Injectors; and I do hereby declare that the following is a full, clear, and exact description thereof, reference being had to the accompanying drawings, in which—

10 Figure 1 shows a vertical section of my improved injector through the axial lines of the lifting apparatus and forcing apparatus and the valve-connection, a portion only of such connection being shown in section. Fig. 2 is a horizontal section on line $x-x$ of Fig. 1. Fig. 15 3 is a vertical section through the axial line of the valve-connection, on line $y-y$, and at right angles to the plane of the section represented in Fig. 1, a portion only of the valve-connection being shown in section. Figs. 4 and 5 show plan views of the steam-admission 20 valve on its seat in different positions, and show in section steam-passages leading to the lifting apparatus and forcing apparatus, respectively. Fig. 6 is a plan view of the upper portion of the valve-connection and the 25 top of the overflow-valve, together with the bonnet removed from the machine. Fig. 7 is a horizontal section through the instrument on line $z-z$ of Fig. 1, looking from above, the 30 seat of the overflow-valve being in section, and the position of the overflow-valve below being indicated by dotted lines. Fig. 8 is a horizontal section of the overflow-valve seat 35 on the same line $z-z$, Fig. 1, looking from above, but the overflow-valve is shown in a different position, as indicated by the dotted lines. Fig. 9 is a plan view of the overflow-valve seat, looking from below, when the valve 40 and bonnet are removed. Fig. 10 is a perspective view of one of the caps which hold in place the steam-jet tube of the lifting and of the forcing apparatus, and Fig. 11 is a similar view of a modification of the cap 45 shown in Fig. 10.

Letters of like name and kind refer to like parts in each of the figures.

My invention is an improvement upon the injector patented to John T. Hancock Janu-

ary 2, 1877, No. 185,861, known as the "inspirator," and its object is, first, to so arrange the lifting-injector apparatus of the inspirator relatively to its forcing-injector apparatus that the admission of steam to the steam-jet tube of each and the opening and closing of overflows for each are controlled by two valves connected to and operated by a single stem controlled by a single handle; second, to provide each apparatus of the combined instrument with a free outlet or 55 overflow to the atmosphere substantially in a direct line with the axial line of each apparatus, in order that the fluid issuing from the combining-tube of each may be discharged into the free air in starting the injector by a 60 direct and unobstructed passage, thereby lessening the detrimental effect of friction due to abrupt changes in the course of the discharged current; third, to so arrange the chambers and water-passages in the instrument when 65 it is set vertically with the overflow-pipe at the bottom that when steam has been shut off from the instrument the water remaining in it shall all run out at the overflow-pipe, or back into the well, thereby obviating 70 danger from freezing, and enabling the lifting apparatus to start readily; fourth, to simplify the construction and permit easy access to the several tubes without disturbing the steam-and-water connections, and, fifth, 75 to hold the steam-jet tube of the lifting apparatus and the steam-jet tube of the forcing apparatus firmly in place by means of the cap-nuts which close the top of the steam-chamber of each of said apparatus. 85

The casing of the injector is designated by A B. The pipe for the admission of the actuating steam is to be connected with the chamber S. The pipe communicating with the well or reservoir is to be connected at W, and 90 the pipe for the delivery or discharge of water to the boiler is to be connected at K.

The steam-jet tube of the lifting apparatus is at a, and its combining-tube is at b. Steam is supplied to it from the chamber S through 95 a port v' in the seat v , controlled by the portion V' of the valve V , and through passage D and chamber D', and the water rises in the

passage W and around the exterior of the combining-tube b and enters the latter at the space between the tubes a and b.

The steam-jet tube of the forcing apparatus is at c, and its combining-tube is at d. Steam is supplied to it from the chamber S through a port v² in the seat v, controlled by the portion V⁴ of the valve V, and through passage E and chamber E', and the fluid delivered from the lifting apparatus rises in the passage or chamber J and around the exterior of the combining-tube d and enters the latter at the space between the tubes c and d. The chamber J, as shown in Figs. 1, 2, and 3, extends around the exterior of the lower end of the chamber N², hereinafter described, a portion of the delivery-chamber K, and the combining-tube d.

The steam-admission chamber S is formed in a bonnet which is screwed to the body of the instrument. Within this chamber is the flat raised seat v of the steam-admission valve V, formed on or attached to the body of the instrument. The steam-admission valve V, located within this chamber, is a disk-valve having projections V³ and V⁴, controlling the ports v' and v², respectively. A recess is formed in its under side, symmetrical to its axis, into which the flattened end N' of the connection N loosely fits, so that the valve must turn when the connection is turned, but which admits of a slight movement of the valve in other directions in order that it may remain in contact with its seat, even if the seat for any reason is not in a plane exactly at a right angle to the axis of revolution of the stem, and to allow for wear of the valve or its seat and for wear of the overflow-valve L and its seat, hereinafter described. By removal of the bonnet, within which is the steam-chamber S, the valve V can be removed by merely lifting it from off the stem, and access can then be readily had to its seat. When the instrument is in operation, this valve is held to its seat by the pressure of steam in the chamber S, and the interior contour of the bonnet is so formed as to act as a stop to prevent it from being disengaged from the stem whenever the pressure is removed.

In the body of the instrument a cylindrical chamber N² is formed intermediate between and connecting the steam-chamber S at the top of the instrument with the overflow-valve chamber M⁶ at its bottom, within which, loosely fitting, the connection N is journaled. The overflow-valve chamber M⁶ is constructed similarly to the steam-admission chamber, being formed in a bonnet M, screwed to the body of the instrument. Within this chamber is the flat raised seat l of the overflow-valve L, formed on or attached to the body of the instrument and provided with two ports, one l' communicating with the chamber J and the other l² communicating with the chamber K. The overflow-valve L, located within this chamber, is a hollow cylindrical disk-valve

having depressions L³ L⁴ in its face and provided with ports L' L², which register with the ports l' and l², respectively, in its seat. Through the ports L' and L² communication is afforded for the direct passage of fluids discharged from chambers J and K to the hollow interior of the valve L and through its hollow prolongation O to the free air. This valve L is also provided with lugs or projections L⁵ and L⁶ on its periphery, which, as they respectively come in contact with a pin p, attached to the body of the instrument, limit the motion of the valve. The hollow prolongation O of the valve L projects through the bonnet M, and to its projecting end is attached a handle P, by means of which, in operating the machine, the movements of the valve L and the valve V (by means of the connection N, which is shown as a stem formed integral with valve L) are controlled.

The connection N, by means of which the valves V and L are connected in the intermediate chamber N², instead of being made integral with the valve L or rigidly attached to it, may be made independent of it and be loosely fitted in a recess in the valve L like that in the valve V.

Within the bonnet M, at its lower part, a space is formed to receive an elastic packing M' to prevent leakage around the tubular prolongation O, which is confined in position by a gland M², loosely fitted in the bonnet and around the tubular prolongation O, and by a spring M³ interposed between the enlarged portion of the valve L and the gland M². It is also compressed around the tubular prolongation O, when the instrument is in operation, by water admitted from the chamber K, through the port l² and the depression L³ in the seating-surface of the valve L, thence around the exterior of the enlarged portion of the valve L in the overflow-valve chamber, and through ports M⁴, formed in a shoulder in the bonnet M beneath the valve L. These ports M⁴ are partially shown in plan in Fig. 7, and one of them is shown in elevation in Fig. 1. The object of thus admitting the water into the overflow-valve chamber is not only to hold the packing-ring M' confined in position, but primarily to hold the valve L up to its seat against the pressures which exist in chambers J and K.

In order to prevent the removal of the valve L from its seat when there is no pressure beneath it in the interior of the overflow-valve chamber M⁶, a shoulder M⁵ is formed, between which and the seat l there is space enough for the valve L to be moved on its seat freely, but not enough to allow more than a slight movement away from its seat. If the spring M³ be made stiff enough to hold the valve L to its seat against the pressure in the chambers J and K, the shoulder M⁵ in the interior of the overflow-valve chamber will not be necessary; and if the valve L be then modified so as to shut off the influx of water to the

overflow-valve chamber from the delivery chamber K, when the instrument is in full operation, the elastic packing M may also be omitted.

- 5 The steam-chambers D' and E' are closed at the top by caps F, which not only serve this purpose, but also hold in position the steam-jet tubes *a* and *c*. Each is provided with a screw-thread F², which fits in the threaded body of the instrument, and with a shoulder F', which, when the cap is screwed down, closes the top of the chamber. One or more projections F³, Fig. 10, are provided, extending below the threaded portion of the cap, 15 which are made long enough to bear upon the steam-jet tube before the shoulder F comes to its seat on the body. When the cap-nut is screwed down to its seat, the projections F³ are sprung inwardly, being thereby shortened, 20 and thus hold the jet-tube firmly in position. This construction allows for slight variations in the relative distances between these parts, whether due to workmanship or expansion and contraction of the body, or to wear.
- 25 Instead of deflecting the spring projections, they may project straight below the cap and be made long enough to bear upon the steam-jet tube before the shoulder F' comes to its seat. In this construction, when the cap-nut is screwed down, the projections F³, if made, 30 as they should be, of comparatively small area, will be compressed and will thus hold the steam-jet tube firmly in position. By removing the cap-nuts it is apparent that the 35 steam-jet tubes may be lifted out and easy access had to remove the combining-tubes or obstructions in them.

The operation of the instrument is as follows: When the handle P is turned to put the 40 valves V and L in the positions shown in Fig. 1, steam is shut off from the apparatus, as both the ports v' and v² are closed, and the ports L' and L² in the overflow-valve L are partially open, so that an outlet is afforded 45 from both the lifting apparatus and the forcing apparatus to the free air. Upon turning the handle P to bring the valve V into the position shown in Fig. 4 from the position shown in Fig. 1, and by the dotted lines in 50 Fig. 5, steam will be admitted through the port v', the passage D, and chamber D' to the steam-jet tube *a* of the lifting apparatus. The port v² remaining covered, the steam is still 55 cut off from the forcing apparatus. This movement of the handle P will have turned the overflow-valve L to the position shown in Fig. 8, so that its port L' will register with the port l' in the seat *l*, and the port L² will register with the enlarged lower part of the 60 port l². An unobstructed passage to the atmosphere from the chamber J is thus afforded through the ports l' L' and the hollow prolongation O. A portion of the steam may 65 pass up through the chamber J and through the combining-tube *d* of the forcing apparatus into the chamber K, whence it will have free

course to the air through the ports l² and L² and the hollow prolongation O. When water rises from the well or reservoir as a result of this action of the lifting apparatus, it will 70 pursue the same course through the instrument as did the steam, and it will be discharged at the lower end of the hollow prolongation O. When the water appears at O, (showing that the lifting apparatus is 75 in operation,) the handle P is turned farther in the same direction as before, and the port L' of the overflow-valve will be moved so that it will cease to register with the port l', while the port L² will still register 80 with the port l². In the meantime the port v' will remain open, and the port v², through which steam is admitted to the forcing apparatus, will remain closed until at or about the time when the overflow from the lifting 85 apparatus is cut off by the valve L. The lifting apparatus will now be fully in operation, and the water delivered from it must pass through the chamber J, through the combining-tube *d* of the forcing apparatus, 90 and into the chamber K, whence, as before, it escapes to the atmosphere through the hollow prolongation O. The handle P being now turned still farther in the same direction as before, the port v² in the steam-valve seat 95 will be opened and steam will thus be admitted through the passage E and chamber E' to the steam-jet tube *c* of the forcing apparatus, where it will act upon the water passing through the tube *d* and accelerate its 100 velocity. After the port v² is wide open the further movement of the handle P in the same direction as before will cause the port L² to no longer register with the port l² in the seat, and consequently the escape to the atmosphere through O will be cut off and the 105 water discharged from the forcing apparatus will be delivered to the boiler through a pipe connected to the chamber K. The steam-valve will then be in the position shown in 110 Fig. 5 and the overflow-valve in that indicated by dotted lines in Fig. 7, the stop L⁶ being in contact with the pin *p*. The combined apparatus will now be in full operation, raising water and delivering it to the 115 boiler, as does the inspirator. The overflow-valve L, as has been described, will be held tightly against its seat by water admitted from the chamber K through the port l', the depression L³ around the exterior of the enlarged portion of the valve, and through 120 ports M¹ beneath the valve, and at the same time the packing M' will be held compressed, so as to prevent any leakage around the exterior of the prolongation O.

125 Instead of the packing M' and gland M², located as described, a stuffing-box of the usual construction may be applied on the outside of the bonnet.

130 Chamber N² need not be closed, for the steam-valve V, if tight, prevents any access of steam to this chamber, and the overflow-

valve L similarly prevents leakage into it from below. The casing may be cut away, as indicated by the dotted lines at Q, and the handle P or other device to manipulate the connection N could be applied at this point. There is an advantage, however, in having this chamber closed, as shown in the drawings, for if the steam-valve happens to leak the overflow-valve, if tight, will prevent the leakage from entering the overflow-chamber or the chambers J and K, and vice versa, and thus leakage is doubly guarded against.

It is obvious that my improved arrangement of the steam and overflow chambers with the valves controlling, respectively, the admission of steam and the overflow to the atmosphere, is equally well adapted to a single lifting apparatus or forcing apparatus as to the combined apparatus herein shown and described. For example, if a lifting apparatus only is desired, the portion V^4 of the valve V and the corresponding port v^2 in its seat would be dispensed with, the port L^2 would be closed, the tubes of the forcing apparatus and their inner closing-chambers would be removed, and the chamber J would be made to discharge into the chamber K. The port l^2 should remain to afford a connection with the overflow-chamber, as before. If a forcing apparatus is desired, it would only be necessary to substitute the tubes c and d for the tubes a and b in the chamber in the casing A of the apparatus as modified for a lifting apparatus.

Having thus described my invention, what I claim is—

1. In an injector, a steam-chamber containing a valve to control the admission of steam, and an overflow-chamber containing a valve to control the overflow to the atmosphere, the two chambers being connected by an intermediate chamber N^2 , communication between the steam-chamber and the overflow-chamber through the intermediate chamber being prevented by one or both of the valves, substantially as described.

2. In an injector, a steam-chamber and an overflow-chamber, a valve in the former to control the admission of steam and a valve in the latter to control the overflow to the atmosphere, the two valves being connected to and operated by a single stem, substantially as described.

3. In an injector, a steam-chamber containing a valve to control the admission of steam, and an overflow-chamber containing a valve to control the overflow to the atmosphere, the two valves being connected to and operated by a stem extending through the valve-seats, leakage around which is prevented by the valves, substantially as described.

4. In an injector containing two sets of jet apparatus, a steam-chamber and an overflow-chamber, a valve in the former to control the admission of steam to each apparatus and a valve in the latter to control the overflow to

the atmosphere from each, the two valves being connected to and operated by a single stem, substantially as described.

5. In an injector, a steam-chamber and an overflow-chamber, and an intermediate chamber N^2 , connecting the two, the steam-chamber being provided with a valve to control the admission of steam, the overflow-chamber with a valve to control the overflow to the atmosphere, the two valves being joined by a connection in the intermediate chamber, whereby the movement of one of the valves operates the other, substantially as described.

6. In an injector containing two sets of jet apparatus, the combining-tubes of which converge in the direction of the flow of the fluid through them, an outlet or overflow passage to the atmosphere, located substantially in line with the respective axial lines of the two combining-tubes, whereby the fluid issuing from each combining-tube is discharged into the free air by a direct passage, substantially as and for the purpose described.

7. In an injector, a valve controlling the admission of steam and a valve controlling the overflow to the atmosphere, the two valves being connected to each other and operated the one by the other, the discharge-outlet from the overflow-valve being formed within a prolongation of that valve, substantially as described.

8. In an injector, an overflow-valve located in a chamber the interior of which is provided with a shoulder, between which and the valve-seat there is space enough to permit the valve to be rotated freely on its seat, but not enough to allow more than a slight movement away from its seat, substantially as and for the purpose described.

9. In an injector, an overflow-valve having a discharge-outlet to the atmosphere formed in its prolongation and located in a chamber, in combination with a spring whereby the valve is held against its seat, substantially as and for the purpose described.

10. In an injector, an overflow-valve having a discharge-outlet to the atmosphere formed in its prolongation and located in a chamber, a passage from the delivery-chamber of the injector extending into the overflow-valve chamber and beneath the exterior of the valve, whereby, when the injector is in operation, the valve is held against its seat by water under pressure, substantially as described.

11. In an injector, an overflow-valve having a discharge-outlet to the atmosphere formed in its prolongation and located in a chamber provided with elastic packing about the exterior of the prolongation, a passage from the delivery-chamber of the injector extending into the overflow-valve chamber, whereby, when the injector is in operation, the valve is held against its seat and the packing about its prolongation is compressed.

by pressure of the fluid thus admitted to the overflow-valve chamber, substantially as described.

12. In an injector, a cap-nut F, provided with a shoulder F', a screw-thread F², and one or more projections F³, in combination with the casing of the injector and the steam-jettube, whereby, when the cap-nut is screwed to its seat, the steam-chamber is closed and

the steam-jet tube is held firmly in position, substantially as and for the purpose described.

In testimony that I claim the foregoing I have hereunto set my hand this 22d day of May, 1888.
